(57) **CLAIM**

The ornamental design for an electronic token and data carrier receptacle, as shown.

DESCRIPTION

FIG. 1 is a top perspective view of an electronic token and data carrier receptacle showing our new design;

FIG. 2 is a bottom perspective view thereof;

FIG. 3 is a top view thereof;

FIG. 4 is a bottom view thereof;

FIG. 5 is a side view thereof;

FIG. 6 is a rear end view thereof; and,

FIG. 7 is a front end view thereof.

The broken lines depict unclaimed environmental subject matter.
